UNITED STATES PATENT OFFICE

HARRY F. WANAMAKER, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

STRIPPING MECHANISM FOR AUTOMATIC HOSIERY DRIERS

Application filed February 15, 1932. Serial No. 593,073.

This invention relates to machines for removing stockings from forms, such as that disclosed in U. S. Letters Patent No. 1,126,619, dated January 26, 1915.

5 In machines of this type, a form with a stocking thereon is placed in a substantially horizontal position with the foot portion thereof disposed between the relatively movable jaws of two pairs of grippers, one operating pair being adapted to grip the heel portion of the stocking while the other cooperating pair is arranged to grip the foot portion of the stocking. The cooperating pairs of jaws are arranged to be simultaneously closed to grip the stocking therebetween, after which the stocking form is moved relative to the jaws in a substantially horizontal plane to withdraw the form from the stocking while the stocking is held between the jaws of the grippers, the grippers being subsequently opened to permit the stocking to fall onto a suitable table or other support.

20 In the course of development of these machines the grippers have been elongated in a direction of the length of the foot portion of the form to distribute the pressure of the grippers over a greater area of the stocking carried by the form, in order to avoid damage to the stocking as the form is being withdrawn therefrom in the manner disclosed in the above-mentioned patent.

25 In the present case the pair of grippers that is adapted to grip the heel portion of the stocking is relatively smaller than the other pair of grippers which is arranged to grip the foot portion of the stocking.

30 Normally the jaws of the grippers, and particularly the gripping surfaces thereof, were composed of non-corrosive metal. With the finer grades of hosiery, metal, contacting with the stocking fabric, tends to injure the delicate fabric.

To overcome this objection the gripping surfaces of the jaws were provided with a relatively soft cushioning material such as rubber, leather, or other non-metallic substance. While this substitution attained the result for which it was intended it introduced another difficulty, which it is the object of this invention to overcome, that is, the fabric

of the stocking has a tendency to adhere to the gripping jaws after the jaws have been opened to release the stocking. In order to remove the stocking immediately from the jaws of the gripper, stripping mechanism, forming the subject of the present invention, has been introduced and combined with the grippers in a manner fully disclosed hereinafter, reference being had to the accompanying drawings, of which:

55 Fig. 1 is a plan view of the gripper arranged to grip the foot portion of the stocking, with the stripper of the present invention applied thereto;

60 Fig. 2 is a front elevation of the mechanism shown in Fig. 1;

65 Fig. 3 is a sectional elevation taken on the line 3-3, Fig. 1 with the jaws in a closed or gripping position;

70 Fig. 4 is a view similar to Fig. 3 with the jaws shown in the opening position; and

75 Fig. 5 is a detached plan view of the stripper.

75 As disclosed in the above-mentioned patent, and as shown in the present drawings, the grippers are carried by a non-rotatable rod 1 and are adapted to be operated by a relatively rotatable rod 2 arranged substantially parallel to the supporting rod 1 and to be rotated with respect thereto by mechanism forming no part of the present invention.

80 The gripper comprises a sleeve 3, which is rotatably mounted on the rod 1. The sleeve 3 is provided with depending lugs 4, 4, from which extend arms 5, 5. The arms 5, 5 are integrally connected at their outer ends by a suitable head 6 in which is arranged one of the elongated gripping elements 7.

85 Pivoted on a pin 8, passing through the two lugs 4, 4, is one end of a link 9, the opposite end of which is pivoted on a pin 10 passing through lugs 11, 11 which form part of an operating lever 12. The lever 12 is splined or otherwise secured against relative rotation to the operating shaft 2, which in the present instance is of a square cross-section, as illustrated in Figs. 1, 3 and 4.

90 Rotatably mounted on the rod 1 adjacent the hub 3 is a similar hub 13 having up-

wardly projecting lugs 14, 14 from which extend integral arms 15, 15 that are integrally connected at their outer ends by a head 16. The head 16 is provided with a gripping element 17 that is arranged to cooperate with the gripping element 7 of the lower jaw structure to grip a stocking form α with the stocking α^1 thereon, in the manner illustrated in Fig. 3.

10 Pivoted on a pin 18 passing through the lugs 14, 14 is one end of a link 19, the opposite end of which is pivoted on a pin 20 carried by lugs 21, 21 forming part of the operating lever 12.

15 Rotation of the shaft 2 from the position shown in Figs. 1, 2 and 3 to that shown in Fig. 4 will cause the jaws of the gripper to be swung from the position shown in Fig. 3 to that shown in Fig. 4, wherein the gripping surfaces 7a and 17a of the gripping elements 7 and 17 respectively are moved in opposite directions to release the stocking α^1 from the said gripping surfaces.

20 The stocking tends to adhere to the gripping surface of one of the jaws and most frequently to the gripping surface 7a of the lower jaw and for the purpose of releasing or stripping the stocking from the lower gripping surface 7a a stripping element 25 is provided.

25 In the preferred form of the invention, the stripper 25 comprises a plate 26 which substantially covers the head 6 of the lower jaw and is provided with an aperture 27, through which the gripping element 7 projects when in gripping contact with a stocking α^1 on a form α .

30 The gripper 25 normally occupies an inoperative position below the plane of the gripping surface 7a, as shown in Fig. 3, and is arranged to be moved to an operative position above the plane of the gripping surface 7a, as shown in Fig. 4, for lifting the stocking from said gripping surface.

35 The plate 26 of the stripper 25 is provided with a rearwardly extending portion 28 having downwardly extending lugs 29 and 30 which extend around the opposite sides of the spaced lugs 4, 4, in which the link 5 of the lower jaw is pivoted, the pivot pin 8 for the said link 5 passing through the lugs 29 and 30 of the stripper and pivotally attaching the said stripper to the said lower jaw.

40 The lug 30 is provided with a rearwardly extending arm 31 which is adapted to be engaged by one end of the pin 10 extending beyond one of the lugs 11 of the actuating lever 12 when the said lever is rocked to move the jaws from the open position shown in

45 Fig. 4 to the closed position shown in Fig. 3. Engagement of the arm 31 by the pin 10 of the lever 12 swings the stripper 25 about its pivot 8, moving the said stripper to its inoperative position below the plane of the gripping surface 7a prior to the closing of the

jaws and the contacting of the gripping surfaces 7 and 17a with the stocking α^1 on a form α subsequently inserted between the jaws.

50 The stripper 25 is adapted to be moved from its inoperative position shown in Fig. 3 to its operative position shown in Fig. 4 by any suitable resilient means, such as a spring 32 confined between the lower side of the plate 26 and the upper side of one of the arms 5, or a bridge element 33 extending across the space between the arms 5, 5 of the lower jaw for supporting the lower end of the spring 32.

55 Movement of the stripper 25 in its operative position is limited by a lug or lip 34 extending inwardly from a downwardly projecting flange or apron 35 disposed at the outer edge of the plate 26 of the stripper 25, the lug 34 being arranged to engage the lower surface of the head 6 of the lower jaw.

60 With the above noted arrangement of elements the stripper 25 functions simultaneously with the opening of the jaws to release the stocking, the pin 10 moving away from the arm 31 of the stripper during the initial jaw-opening movement of the lever 12 and permitting the spring 32 to move the stripper 25 to its operative position substantially at the same time as the gripping surface 17a moves away from the gripping surface 7a and from the stocking gripped between the two said gripping surfaces.

65 I claim:

1. In a machine for removing stockings from forms, the combination of a pair of cooperating jaws for gripping a stocking on a form, and means for stripping the stocking from the grippers subsequent to the removal of the form from the stocking.

70 2. In a machine for removing stockings from forms, the combination of a pair of horizontally disposed relatively movable jaws for gripping a stocking on a form therebetween, and means cooperating with the lower jaw of said pair for stripping the stocking therefrom subsequent to the removal of the form from the stocking.

75 3. In a machine for removing stockings from forms, the combination of a pair of horizontally disposed relatively movable jaws for gripping a stocking on a form therebetween, and means cooperating with the lower jaw of said pair for stripping the stocking therefrom subsequent to the removal of the form from the stocking, said stripper comprising an element disposed adjacent the gripping surface of said lower jaw and movable to a plane above said gripping surface to strip the stocking therefrom.

80 4. In a machine for removing stockings from forms, the combination of a pair of horizontally disposed relatively movable jaws for gripping a stocking on a form therebetween, and means cooperating with the lower jaw of said pair for stripping the stock-

ing therefrom subsequent to the removal of the form from the stocking, said stripper comprising an element surrounding the gripping surface of said lower jaw and movable to a plane above said surface to strip the stocking therefrom.

5. In a machine for removing stockings from forms, the combination of a pair of horizontally disposed relatively movable jaws for gripping a stocking on a form therebetween, means cooperating with the lower jaw of said pair for stripping the stocking therefrom subsequent to the removal of the form from the stocking, said stripper comprising an element surrounding the gripping surface of said lower jaw and normally disposed in a plane below that of said surface, and means for raising said element to a plane above that of said surface to strip the stocking therefrom.

6. In a machine for removing stockings from forms, the combination of a pair of horizontally disposed relatively movable jaws for gripping a stocking on a form therebetween, means cooperating with the lower jaw of said pair for stripping the stocking therefrom subsequent to the removal of the form from the stocking, said stripper comprising an element completely surrounding the gripping surface of said lower jaw and normally disposed in a plane below that of said surface, and means for raising said element to a plane above that of said surface to strip the stocking therefrom.

33. 7. In a machine for removing stockings from forms, the combination of a pair of horizontal disposed relatively movable jaws for gripping a stocking on a form therebetween, means cooperating with the lower jaw of said pair for stripping the stocking therefrom subsequent to the removal of the form from the stocking, said stripper comprising a plate normally disposed below the plane of the gripping surface of said jaw and provided with an opening through which said gripping surface projects, and means for raising the plate to a plane above that of said surface to strip the stocking therefrom.

8. In a machine for removing stockings from forms, the combination of a pair of horizontally disposed relatively movable jaws for gripping a stocking on a form therebetween, means cooperating with the lower jaw of said pair for stripping the stocking therefrom subsequent to the removal of the form from the stocking, said stripper comprising a plate normally disposed below the plane of the gripping surface of said jaw and provided with an opening through which said gripping surface projects, means for raising the plate to a plane above that of said surface to strip the stocking therefrom, and means for returning said plate to its normal position prior to the closing of the jaws into grip-

ping contact with a stocking on a form subsequently positioned between the jaws.

9. In a machine for removing stockings from forms, the combination of a pair of horizontally disposed relatively movable jaws for gripping a stocking on a form therebetween, means cooperating with the lower jaw of said pair for stripping the stocking therefrom subsequent to the removal of the form from the stocking, said stripper comprising a plate normally disposed below the plane of the gripping surface of said jaw and provided with an opening through which said gripping surface projects, resilient means for raising the plate to a plane above that of said surface to strip the stocking therefrom and means for returning said plate to its normal position prior to the closing of the jaws into gripping contact with a stocking on a form subsequently positioned between the jaws.

10. In a machine for removing stocking from forms, the combination of a pair of jaws adapted to grip a stocking on a form between cooperating gripping surfaces of the said jaws respectively, means for pivotally supporting said jaws, actuating means for opening and closing said jaws, a stripper cooperating with one of said jaws to strip the stocking from the gripping surface thereof, and means for moving the stripper to operative and inoperative positions respectively during the operation of said jaws by said actuating means.

11. In a machine for removing stockings from forms, the combination of a pair of jaws adapted to grip a stocking on a form between cooperating gripping surfaces of the said jaws respectively, means for pivotally supporting said jaws, actuating means for opening and closing said jaws, a stripper cooperating with one of said jaws to strip the stocking from the gripping surface thereof, means for moving the stripper to an operative position relative to said surface to strip the stocking therefrom, and means operable by said jaw actuating means to move the stripper to an inoperative position relative to said surface prior to the gripping of a stocking and its form subsequently inserted between said jaws.

12. In a machine for removing stockings from forms, the combination of a pair of jaws adapted to grip a stocking on a form between cooperating gripping surfaces of the said jaws respectively, means for pivotally supporting said jaws, actuating means for opening and closing said jaws, a stripper cooperating with one of said jaws to strip the stocking from the gripping surface thereof, resilient means for moving the stripper to an operative position relative to said surface to strip the stocking therefrom simultaneous with the opening of the jaws by said actuating means, and means operable by said jaw actuating means to move the stripper to an inoperative

position relative to said surface prior to the gripping of a stocking and its form subsequently inserted between said jaws.

13. In a machine for removing stockings from forms, the combination of a pair of jaws adapted to grip a stocking on a form between cooperating gripping surfaces of the said jaws respectively, means for pivotally supporting said jaws, actuating means for opening and closing said jaws, a stripper pivotally mounted on one of said jaws and cooperating with the gripping surface thereof to strip the stocking therefrom, resilient means for moving the stripper to an operative position relative to said surface simultaneous with the opening of said jaws by said actuating means, an arm on said stripper, and a projection on said actuating means adapted to engage said arm to move said stripper to an inoperative position relative to said surface prior to the gripping of a stocking and its form subsequently inserted between said jaws.
14. In a machine for removing stockings from forms, the combination of a pair of jaws adapted to grip a stocking on a form between cooperating gripping surfaces of the said jaws respectively, means for pivotally supporting said jaws, actuating means for opening and closing said jaws, a stripper pivotally mounted on one of said jaws and cooperating with the gripping surface thereof to strip the stocking therefrom, resilient means for moving the stripper to an operative position relative to said surface simultaneous with the opening of said jaws by said actuating means, means for limiting the movement of said stripper in its operative position relative to the gripping surface with which it cooperates, an arm on said stripper, and a projection on said actuating means adapted to engage said arm to move said stripper to an inoperative position relative to said surface prior to the gripping of a stocking and its form subsequently inserted between said jaws.

HARRY F. WANAMAKER.
